W. H. ELLIOTT.
COMPOSITE RAILWAY TIE.
APPLICATION FILED DEC. 3, 1919.

Patented Feb. 24, 1920.

WITNESS,

William P. Thickettun

By
Clarence A. O'Brien,
Attorney.

UNITED STATES PATENT OFFICE.

WILLIAM HOWELL ELLIOTT, OF WASHINGTON, DISTRICT OF COLUMBIA.

COMPOSITE RAILWAY-TIE.

1,331,809.

Specification of Letters Patent.

Patented Feb. 24, 1920.

Application filed December 3, 1919. Serial No. 342,099.

To all whom it may concern:

Be it known that I, WILLIAM H. ELLIOTT, a citizen of the United States, residing at Washington, in the District of Columbia, 5 have invented new and useful Improvements in Composite Railway-Ties, of which the following is a specification.

The object of my present invention is the provision of a simple, inexpensive and durable railway tie, of composite type, and one in which the weight imposed on the rails is adequately cushioned and undue noise is eliminated.

To the attainment of the foregoing, the 15 invention consists in the improvement as hereinafter described and definitely claimed.

In the accompanying drawings, hereby made a part hereof:

Figure 1 is a broken view showing in side 20 elevation a tie constructed in accordance with my invention.

Fig. 2 is a fragmentary view taken at right angles to Fig. 1, and showing a plurality of the ties in end elevation.

Fig. 3 is a detail view of a modification.

Similar numerals designate corresponding parts in Figs. 1 and 2 to which reference will first be had.

The rails 1 and the rail-holding elements 30 2 are not of the essence of my invention, and may, therefore, be of any appropriate construction.

My novel tie comprises lower and upper metallic sections 3, preferably of wrought 35 iron, and corresponding in length and width, and interposed and comparatively short sections 4 of a comparatively soft metal or alloy, preferably copper. Any approved means may be employed to tie or 40 connect the sections 3 and 4 together and to the rail-holding elements 2, without affecting my invention, though I prefer to employ bolts 5 for the purpose; the said bolts being provided with heads 6, disposed in 45 countersinks in the under side of the lower section 3, and being equipped with nuts 7.

The sections 4 are separated by an intervening space 8, and are spaced from the ends of the sections 3, as indicated by 9. By 50 reason of this arrangement of the comparatively soft metallic sections 4 relatively to the metallic sections 3, and the rails superimposed upon the upper section 3 above and in the same vertical planes as the sections 4, 55 the capacity of the sections 4 to cushion the rails and to lessen noise incidental to trains

traversing the rails, is materially increased. This will be fully understood when it is stated that the hard metal sections 3 are free to move toward each other between the 60 sections 4, and also beyond the outer ends of the sections 4, so that in effect the sections 4 alone sustain the upper section 3 and rails 1, and the weights imposed on the latter.

While I prefer to employ interposed sections of comparatively soft metal or alloy in combination with the hard metal sections 3, I do not desire to be understood as confining myself to such interposed sections. This is 70 exemplified in Fig. 3 wherein I show as interposed between the hard metal or wrought iron sections 3, a comparatively soft section 4^a of wood, fiber or the like, and in this connection it is to be understood that when 75 wood or fiber sections 4^a are employed, they will be arranged in the same manner as the soft metal sections 4 in Fig. 1, relatively to the sections 3, the rail-holding elements 2 and the bolts 5.

In addition to the practical advantages ascribed to my novel tie, it will be appreciated that the tie is not unduly expensive, is well adapted to withstand the usage to which railway ties are ordinarily subjected, 85 and, in proportion to its strength and durability, is light in weight.

Having described my invention, what I claim and desire to secure by Letters-Patent, is:

1. A composite railway tie comprising upper and lower hard-metal sections corresponding in length and width, comparatively short and soft metallic sections interposed between the hard-metal sections and separated by an intervening space and also separated by spaces from the ends of the hard-metal sections, rail-holding elements on the upper hard-metal section in vertical alinement with the interposed sections, and means connecting the hard-metal sections together and to the interposed metallic sections.

2. A composite railway tie comprising upper and lower hard-metal sections corresponding in length and width, comparatively short and soft cushioning sections interposed between the hard-metal sections and separated by an intervening space and also separated by spaces from the ends of the hard-metal sections, rail-holding elements on the upper hard-metal section in

vertical alinement with the interposed sections, and means connecting the hard-metal sections together and to the interposed cushioning sections.

- 5 3. A composite railway tie comprising upper and lower hard-metal sections, soft metal means interposed between said hard-

metal sections, rail-holding elements on the upper sections, and means connecting the hard-metal sections together and to the in- 10 terposed soft-metal means.

In testimony whereof, I hereunto affix my signature.

WILLIAM HOWELL ELLIOTT.
